DOLL'S HEAD

Filed July 12, 1932

UNITED STATES PATENT OFFICE

2,013,631

DOLL'S HEAD

Samuel Kalner and David Cohn, Brooklyn, N. Y.,
assignors to Eyedoll Corporation, Jersey City,
N. J., a corporation of New Jersey

Application July 12, 1932, Serial No. 622,026

5 Claims. (Cl. 46—40)

This invention relates to doll construction, and is particularly directed to a doll's eye unit and mounting for a sleeping doll, and the like devices.

An object of this invention is to provide a highly simplified, durable and strong doll's eye unit and mounting of the character described, which shall be comparatively cheap and simple to manufacture, easy to assemble and adjust with respect to the eye sockets in the doll's head, which shall operate smoothly, and which shall yet be practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

20 In the accompanying drawing, in which is shown one of the various possible illustrative embodiments of this invention,

Fig. 1 is a rear elevational view of the doll's eye unit embodying the invention;

25 Fig. 2 is a cross-sectional view taken on line 2—2 of Fig. 1;

Fig. 3 is a partial rear elevational view of a doll's eye unit illustrating a modified construction;

30 Fig. 4 is a cross-sectional view taken on line 4—4 of Fig. 3;

Fig. 5 is a side elevational view of a doll's eye embodying the invention and adapted to be mounted on the eye support shown in Fig. 1 and

35 Fig. 3;

Fig. 6 is a cross-sectional view taken on line 6—6 of Fig. 5;

Fig. 7 is a partial top plan view of a doll's eye unit illustrating a further modification with parts

40 in cross-section;

Fig. 8 is a rear view taken along lines 8—8 of Fig. 7;

Fig. 9 is a fragmentary, horizontal, cross-sectional view of a doll's head provided with a doll's eye unit and mounting therefor, embodying the invention;

Fig. 10 is a cross-sectional view taken on line 10—10 of Fig. 9;

Fig. 11 is a perspective view of a doll's eye unit

50 illustrating a still further modification; and

Fig. 12 is a perspective view of one of the doll's eyes shown in Fig. 11.

Referring now to the drawing, and particularly to Figs. 1, 2, 9, and 10, H indicates a portion of

55 a doll's head provided with a doll's eye unit and

mounting embodying the invention and formed with a pair of spaced eye sockets 10. The head is provided on the interior thereof at a point between the eye sockets 10, with a rearwardly extending, preferably horizontal, cylindrical extension 10a. Said cylindrical extension 10a is provided with a pair of diametrically disposed, elongated, parallel, T-shaped slots 10b, the crossing portions 10c of said slots being disposed adjacent the base of the extension, for the purpose 10 hereinafter described. The cylindrical extension 10a is provided with internal screw threads 11 receiving an externally screw threaded member 11a provided with a kerf 11b on the outer end thereof, and an axial socket 11c on the inner end 15 thereof.

Disposed within the extension 10a is a pin 12 having a shank portion 12a slidably received within said socket 11c, and a head 12c disposed between the inner end of the screw threaded 20 member 11a and the surface 12b at the bottom of said cylindrical extension. Preferably, the shank 12a is somewhat longer than the socket 11c so that the end of said shank will contact the end of said socket.

25 Mounted on the doll's head H, as hereinafter described, is a doll's eye unit E embodying the invention, comprising a member 13 preferably made of sheet celluloid or the like material, stamped or cut to the shape shown in Fig. 1 of 30 the drawing. Said member 13 comprises a downwardly extending flat arm 13a at the upper end of which there is a crossing portion 13b having at the ends thereof substantially parallel arms 13c.

Attached to the outer ends of said arms 13c, is an elongated tube or rod 15, preferably likewise made of celluloid or the like material, and cemented to said arms as at 16. The rod or tube 15 preferably extends an equal distance on opposite sides of the arms 13c, as at 17. The rod may be cemented or otherwise adhered or attached to one face of the arms 13c adjacent the outer ends of said arms. However, if the member 13 and rod or tube 15 are made of metal, solder or any other attachment means may be used to mount the rod on said member. Pivoted on said extensions 17 are doll's eyes 19. Each of said eyes 19 is preferably hollow and substantially hemispherical in shape and is provided with a substantially cylindrical portion 20 forming a skirt or open rim for the rear of the eye. Each of said eyes 19 is further provided with a pair of aligned, diametric, bearing openings 21, rotatably receiving one of the extensions 17. The eyes pref-

erably frictionally engage the extensions 17 so as to permit the eyes to be swung or adjusted manually, the eyes preferably being frictionally retained on said extensions in any position to 5 which the same may be moved.

The eyes 19 may also be made of sheet celluloid, or any other suitable material, and are painted or otherwise decorated to simulate an eye and eyelid. A weight member 22 made of 10 lead or any other suitable material, may be mounted on the arm 13a of the member 13 to permit the eye unit to swing by the action of gravity when the doll is changed from an upright to a lying position, as will appear herein- 15 after.

As shown in Figs. 9 and 10 of the drawing, the unit E is mounted within the doll's head H by passing the portion of the rod 15 which extends between the arms 13c through the slots 10b into 20 the portion 10c thereof, so that the eye members 19 will be received within the sockets 10. The pin 12 is then inserted in the socket 11c and the screw threaded member 11a screwed within the cylindrical extension 10a so that the head 12a 25 of said pin may contact the mid portion of the rod 15. The screw threaded member 11a may be adjusted to permit the rod 15 to have movement forwardly, rearwardly, upwardly or downwardly so that a perfect fit is assured, irrespective of 30 variations in the position of the sockets during manufacture of the head H. Furthermore the eye members 19 may be rotatably pivoted about the rod 17 or moved along said rod outwardly or inwardly whereby a more perfect adjustment of 35 the eye members 19 with respect to the sockets 10 may be obtained.

In Fig. 3 there is shown a doll's eye unit 23 comprising a member 23a likewise preferably made of celluloid and similarly shaped to member 13a shown in Fig. 1. Said member 23a is 40 preferably of sufficient thickness so as to permit the arms 23b thereof to be formed with aligned bearing openings 25 receiving therethrough a rod or tube 15a, similar to the rod or tube 15. The rod or tube 15a may be fixed to the arms 23b 45 either by friction or by cement, or other adhesive applied at the openings 25. The doll's eyes 19, illustrated in Fig. 1, may be mounted on the extensions 11a of the member 15a. However, as 50 illustrated in Figs. 3 and 4, there is mounted on said extensions, a pair of similar doll's eyes 19a, likewise of substantially hollow hemi-spherical shape and each provided with aligned diametric openings 26.

Attached to each eye 19a is a diametrically disposed tube 27 having ends 28 thereof received within said openings 26. Preferably, each tube 27 is equal in length to the outer diameter of one of the eyes 19a. The end portions 28 may be cemented, glued or otherwise attached to the eyes 60 by means of an adhesive applied as at 29, preferably on the inside of the eye members. Said tubes 27 may also be made of celluloid or any other suitable material. The outer end portions 11a 65 of the rod 15a are preferably frictionally received within the tubes 27 to permit the eye members 19a to be pivotally and axially adjusted on the extensions 11a which serve as axes for said eye members.

In Figs. 5 and 6 there is shown a modified form 70 of eye member 30 adapted to be mounted on the extensions 17 or 11a of the members 13 or 23a, shown in Figs. 1 and 3, respectively. Said eye member 30 comprises a member 31 forming part 75 of a sphere and made of wood or any other suit-

able material. The member 31 is preferably provided with a diametrically disposed bore 32 for frictionally and slidably receiving said extensions 17 or 11a. Said member 31 is further formed with a substantially cylindrical socket portion 32a 5 forming a circular rim flange 33. Attached to said member 31 is an eye ball 34 made of glass or any other suitable material, and comprising a portion 35 completing the sphere formed by the member 31. Extending from said portion 35 is 10 a flange 36 extending into the socket 32a. Cement or any other suitable adhesive may be used for attaching the flange 36 to the surfaces of the socket 32. The portion 35 may be painted in the usual manner to simulate the visible portion of 15 the doll's eye and eyelid.

In Fig. 7 there is shown a still further modified form of doll's eye unit. The unit 40 shown in Fig. 8 comprises a member 41 similar to the member 13, shown in Fig. 3, and has upstanding arms 42 provided with openings receiving therethrough, a rod 44 preferably extending only a short distance beyond said arms 42, as at 45. Attached to each extension 45 is an angle shaped member 46 having an arm 47 provided with an 25 opening receiving therethrough said extension 45, and an arm 48 disposed parallel to the rod 44, said arm 47 being soldered, cemented or otherwise fixed to said rod extensions. The arm 48 is provided, for the purpose hereinafter appearing, with an elongated slot 49. Mounted on said arm 48 is an eye member 50 comprising a hollow member 51 made of glass or any other suitable material, suitably colored or painted to simulate an eye, said member 51 being in the shape of 35 substantially three-quarters of a sphere and having an inwardly extending circular flange 52 provided with a central opening 53. The member 51 may be filled with plaster or any other suitable material, as at 54, and embedded within the material 54 is a screw 55 having a head 56 40 within said material, and a shank 57 extending through the opening 53. As illustrated in Fig. 7, the flange 52 may contact the inner side of the arm 48 and the shank 57 passes through the slot 49. A nut 58 screwed to the shank 57 serves to firmly clamp the eye member 50 to said arm 48. Obviously the eye member 50 may be adjusted along the length of the arm 48 by properly manipulating the nut 58. The material 54 is 50 preferably of such character that it will harden after the screw 55 is positioned therein so as to retain said screw in fixed condition.

It will now be seen that the eye member 50 may pivot about the rod portion 44 of member 41. 55 The rod 44, it will be noted, preferably is aligned with the center of the spherical member 51 so that the eye members 50 may rotate about their axes within the eye sockets of the doll's head.

In Figs. 11 and 12 there is shown a still further 60 modification of a doll's eye unit. Said figures disclose a unit 70 comprising a member 71 made of sheet metal or any other suitable material, and having a downwardly extending portion 72 to which there is attached a weighted member 73. 65 At the upper end of the portion 71 is a crossing portion 74 from which there extends a pair of parallel arms 75. Attached to the upper ends of the arms 75, as by means of soldering or in any other suitable manner, is a tube 76 made of metal 70 or the like suitable material, said tube being open at both ends thereof. Mounted on the opposite ends of said tube, in the manner hereinafter appearing, are a pair of doll's eye members 77, each comprising a hemi-spherical, hollow shell 75

- 78 substantially similar to the member 19, and formed with diametrically disposed notches 79 receiving a rod or tube 80 made of celluloid or the like suitable material, and attached to said eye shell as, for example, by cement. The tube or rod 80 preferably extends on one side thereof, as at 81, beyond the shell 78. The extending portion 81 is preferably slidably and rotatably received within one end of the tube 76. Thus, the pair of 10 members 77 may be mounted on opposite ends of the tube 76. The members 77 may be rotated with respect to the axis of the rods 80 or of the tube 76. Further, said members 77 may be slidably moved inwardly or outwardly for properly 15 adjusting the same so that the shells 78 may fit snugly within the eye sockets of the doll's head H.
- Obviously the eye units shown in Figs. 3, 4, 7, 8, 11 and 12 may be mounted on the doll's head H in 20 the manner illustrated in Figs. 9 and 10.
- It will thus be seen that there is provided a device in which the several objects of this invention are achieved, and which is well adapted to meet the conditions of practical use.
- 25 As various possible embodiments might be made of the above invention, and as various changes might be made in the embodiment above set forth, it is to be understood that all matter herein set forth or shown in the accompanying 30 drawing is to be interpreted as illustrative and not in a limiting sense.
- Having thus described our invention we claim as new and desire to secure by Letters Patent:
1. A doll's eye unit comprising a member, a 35 weight attached to said member, said member having a pair of spaced flat substantially parallel arms, said arms being provided with aligned openings, a cylindrical rod extending through said openings and having portions projecting on opposite sides of said arms, and a doll's eye mounted on each of said projecting portions, each eye being hollow and hemi-spherical in shape and provided with a pair of diametrically disposed openings, a tube having the ends thereof 40 extending into the pair of openings in each eye and receiving one of said projecting portions therethrough.
2. In doll construction, a doll's head formed with a pair of eye sockets, said doll's head having a portion extending between said sockets and internally of said head, said extension being 45 formed with a pair of longitudinal, parallel slots and with internal screw threads, a screw screwed within said extension, said screw threaded member being formed with a recess on the inner end thereof, a pin extending within said recess and projecting therefrom, and a doll's eye unit supported on said extension, said unit comprising a rod extending through said slots and adapted to contact the projecting portion of said pin, and doll's eyes mounted on the outer ends of said rod and disposed within said eye sockets.
3. In doll construction, a doll's head formed with a pair of eye sockets, said doll's head having a cylindrical portion extending between said sockets and internally of said head, said cylindrical extension being formed with a pair of longitudinal, diametrically disposed slots and with internal screw threads, a screw screwed within said cylindrical extension, said screw threaded member being formed with a recess on the inner end thereof, a pin extending within said recess and projecting therefrom, and a doll's eye unit supported on said extension, said unit comprising a rod extending through said slots and adapted to contact the projecting portion of said pin, and doll's eyes mounted on the outer ends of said rod and disposed within said eye sockets.
4. A doll's eye unit comprising a member having a weight attached thereto, a tube attached to one end of said member, and a pair of doll's eyes having rods attached thereto and extending therefrom, said rods being slidably and rotatably received in opposite ends of said tube.
5. In doll construction, a doll's head formed with a pair of eye sockets, said doll's head having a cylindrical portion extending between said sockets and internally of said head, said cylindrical portion being formed with a pair of longitudinal, diametrically disposed slots and with internal screw threads, a screw screwed within said cylindrical portion, and a doll's eye unit supported on said cylindrical portion, said unit comprising a rod extending through said slots, and doll's eyes mounted on the outer ends of said rod and disposed within said eye sockets, said slots being widened at the inner ends thereof and said rod extending within the widened portions of said slots.

SAMUEL KALNER.
DAVID COHN.
